5 fine converging portions 14 and 15 to present a hound wherein a tongue 16 is detachably secured in any appropriate manner, such as by the bolt 17, the tongue 16 serving to harness any suitable means of locomotion thereto.

10 The frame 10 is elevated from the soil by means of a pair of wheels 18 journalled to suitable brackets 19 which are rotatably mounted in vertically disposed bearings 20 secured to the members 11 and 12 in proximity to the forward end thereof whereby the wheels 18 are capable of being turned in any direction for steering purposes. A pair of 15 drive wheels 21 are keyed or otherwise secured to a shaft 22 which is journalled in the frame 10, the latter being provided with suitable bearings 23 to permit rotation of the drive shaft 22. A plurality of cleats 24 of standard construction are secured to the periphery of the wheels 21 to increase the traction of the wheels which serve as a positive drive for the instrumentalities to be herein-after described.

20 Soil embedded crops such as beets have exposed portions 25 to enable their removal from the soil. To accomplish this end, the present invention contemplates the provision of pulling means comprising, in this instance, 25 a carrier constituting a pair of endless conveyors. In the present embodiment the conveyors consist of complementary arcuate sections bolted or otherwise secured together to define rigid members 26 which are provided therein with appropriate gears 27 at their extremities whereto endless chains 28 are geared, the chains being in mesh with the gears 27 to effect positive movement therebetween. A plurality of idler pinions 29 are 30 journalled in the members 26, they being in mesh with the chains 28 so as to support the chains to define an arcuate path corresponding in shape to that of the members 26, the latter being yieldably suspended from the frame 10 so that the mouth of the conveyors 35 will be disposed near the ground at a point within the range of the exposed appendages 25 constituting a part of the soil embedded crops.

40 To enable the exposed portions 25 of the crops to be effectively grasped, the article engaging surfaces of the chains 28 are provided with a flexible band 30 having a substantially rectangular cross-section, the band being secured in a grooved portion 31 provided in the face of the chains 28 to define a raceway therein. Any suitable fasteners may be employed to secure the flexible band 30 to the chains 28, the fasteners in this instance comprising oppositely disposed rivets 32 carried by an auxiliary link 32' flexibly connecting the links constituting the chains, the extremities of the rivets 32 projecting within the flexible band 30 to prevent removal thereof from the raceway 31. The

45 tension of the chains 28 is controlled by means of an arm 33 pivotally mounted as at 34 to the rigid member 26, the free end thereof having a pinion 35 journalled therein to mesh with the chain 28. The pinion 35 is urged outwardly in engagement with the chain 28 to increase the tension thereof owing to a resilient spring 36 which is held in position by means of a rod 37 axially disposed therein, one extremity of the spring 36 impinging against the arm 33 with the other end thereof engaging a portion of the tubular member 26. The urge of the spring 36 automatically tensions the chain 28 and maintains the adjacent surfaces of the flexible bands 30 of each conveyor unit in frictional engagement to effect removal of the crops by engaging the exposed portions thereof, thereby being gradually elevated along the arcuate path defined by the conveyor to effect their removal from the soil. As shown, both conveyors 26 are disposed in a common plane in that they are similar in shape, structure, and contour to effect the desired purpose.

50 The yieldable suspension of the conveyors 26 is, in this instance, effected by means of a spiral spring 38 having one extremity thereof secured to a bell crank 39 which is supported on a suitable standard 40 resting on a cross member 13 constituting a part of the frame 10, the standard 40 being fixed thereto by means of the brackets 41 of standard construction. The other end of the spring 38 is secured to a stud shaft 42, which, in this instance, is operatively connected to a foot pedal 43 through appropriate linkage 44 and 45 having the extremities thereof pivoted to each other and to the shaft 42. A horizontally disposed arm 46 terminating in a vertically disposed portion 47 is integrally or otherwise secured to one of the members 26 near the lower end thereof, the arm 46 being provided with a bore 48 substantially along a median line thereof to receive the stud shaft 42 therethrough. The member 26 of the other conveyor unit is provided with an arm 49 having a bored extremity 50 to receive the stud shaft 42 adjacent to and in alignment with the bore 48 of the arm 46, thereby rendering the conveyor units 26 separable along a common axis, in this instance the shaft 42. A spiral spring 51 is interposed between confronting portions of the arms 46 and 49 which are provided with aligned apertures to receive a bolt 52 therethrough which retains the spring 51 in position to normally tend to spread the free extremities of the arms 46 and 49 whereby the conveyor units 26 are caused to resiliently engage each other. It is to be noted that the conveyors 26 are adjustably suspended owing to the foot pedals 43 whereby the mouth defined by the co-operating conveyors 26 may be laterally adjusted to bring it in alignment with the crops which are usually 55 60 65 70 75 80 85 90 95 100 105 110 115 120 125 130

disposed along a straight line. The crops are guided to the engaging surfaces of the pullers by means of a pair of metal plates 26 secured to the forward ends of the members 26 to define a V-shaped throat which increases the operating range of the machine. The discharge end of the conveyor frames 26 are each provided with normally disposed housings 53 having a flanged extremity 54 therein. The housings 53 are bolted or otherwise secured to the members 26 by means of the fasteners 55 in the usual manner, they being pivotally supported to a standard 54' suitably fixed to the frame 10. The other extremities of the housings 53 terminate in angularly disposed brackets 56 having shaft housings 57 disposed normally thereto to receive a drive shaft 58 therethrough, the drive shaft 58 being journalled in a suitable bearing fixed to the frame 10 in any suitable manner. A pair of stud shafts 59 project through and are journalled within the housings 53, they being secured to the gears 27, supra, through which they project to present exposed extremities 60. The other extremities of the shafts 59 are each provided with bevel gears 61 which mesh with suitable bevel gears 62 secured to the normally disposed drive shafts 58, in this instance two, one of which has both extremities thereof provided with bevel gears 62 meshing with the bevel gears 61 to drive the shafts 59 at a uniform speed in opposed directions. It is to be understood that the shafts 59 are fixed to the gears 27 disposed in proximity to the discharge ends of the conveyor units to drive the conveyor chains 28 in the same direction at a uniform speed so as to prevent slipping between the contacting faces of the flexible bands 30 of each conveyor. The housings 53 are pivotally secured to each other as at 63 in much the same manner as are the forward ends of the conveyors 26, the brackets 56 on one of the housings 53 being provided with a projecting arm 64 having an apertured extremity 65 confronting a projection 66 formed integral with the other housing to receive a bolt 67 therebetween. A spiral spring 68 envelops the bolt 67 to impart an urge to the arm 64 in an effort to bring the discharge end of the conveyor units together, thereby rendering the conveyors separable along the contacting surfaces thereof to permit foreign substances to pass therethrough without injury thereto. The exposed portions of the crops are sheared or otherwise severed from the body thereof, in this instance by means of a pair of oppositely dished circular cutters 69 fixed to the exposed extremities 60 of the shafts 59 which impart opposed rotation thereto, the cutters 69 being disposed in the path of the crops defined by the carrier mechanism hereinabove described.

To insure that all of the appendages

projecting from the soil embedded articles are removed prior to their discharge from the machine, auxiliary severing means are provided. The auxiliary severing means in this instance comprise a pair of cylindrical rollers 70 preferably having a corrugated or otherwise roughened surface, the rollers 70 being driven in opposed directions by means of intermeshing gears 71 fixed to shafts 72 projecting axially of the rollers 70. One of the shafts 72 is connected to a drive shaft 73 journalled in the frame 10, there being a universal or flexible joint 74 interposed between the shafts 72 and 73 to enable the rollers 70 to be inclined to effect the discharge of the articles falling thereon, the rollers 70 being disposed below the discharge end of the conveyor units 26. The shaft 72 which has the flexible connection 74 thereon, is supported in position by means of a bracket 75 which is secured to the frame 10 in any appropriate manner, the other shaft 72 having a bracket 76 fixed to the extremity thereof whereby it is pivotally secured to the bracket 75 in any suitable manner as at 77. A compressible spring 78 is interposed between the frame 10 and the bracket 76 to normally urge the rollers 70 in substantial engagement with each other to grasp any projections remaining on the body of the article which is too large to be drawn therethrough, thereby severing the projections therefrom. A pair of guides 79 comprising substantially rectangular members are associated with each of the rollers 70, they being inclined to each other to prevent the articles falling on the rollers 70 from being displaced therefrom other than the discharge or lower end thereof.

The instrumentalities described above are responsive to movement of the frame 10 occasioned by rotation of the drive wheels 21 which are secured to the shaft 22 having a sprocket wheel 80 keyed or otherwise fixed thereto. A chain 81 meshes with the teeth of the sprocket wheel 80 to drive a gear 82 fixed to a stud shaft 83 journalled in the frame 10. A chain 84 is geared to a sprocket wheel 85 fixed to a stud shaft 86 which is operatively connected to the stud shaft 83 by means of suitable gearing 87. The chain 84 which meshes with the sprocket wheel 86 fixed to the shaft 58, supra, drives the conveying and topping instrumentalities 30 and 69, respectively, at the proper speeds. The auxiliary severing means constituting the rollers 70 are driven by means of a chain 88 operatively connected to the shaft 58 and to the shaft 81 by means of aligned sprocket wheels 89 and 90, respectively. Rollers 70 and the parts appurtenant thereto may be supported upon the frame in any suitable manner, as, for instance, by the transverse members shown intermediate the brackets 92 and 98 in Figure 10.

Loosening means, in this instance a plow 91 of suitable construction is pivotally associated with the frame 10 by means of a depending bracket 92 to which it is secured as at 93. The free extremity 94 of the plow 91 is provided with a slot 95 to receive a stud 96 secured in the bell crank lever 97 which is pivoted to a depending bracket 98 secured to the frame 10 in any appropriate manner such as by the bolts 99.

The position of the plow 91 is remotely controlled, in this instance by a hand lever 100 of standard construction which is pivoted within suitable range to a quadrant 101 having teeth 102 on the arcuate portion thereof to enable adjustment of the lever by means of the thumb control 103 having the usual pawl 104 operatively connected thereto. A rod 105 is secured to the lever 100 as at 106, the other end thereof being operatively connected to a bell crank 107 pivotally secured to the rear end of the frame 10 by means of a pin 108 fixed in an appropriate bracket 109 secured to the frame 10. The bell crank lever 107 has the other arm thereof operatively associated with the free arm of the bell crank lever 97 through the medium of a rod 109' whereby movement of the lever 100 will vary the position of the plow 91 which is effective to loosen the soil about the crops just prior to their removal.

Another hand lever 110 like the lever 100, is operatively associated with a quadrant 101 fixed to the frame 10 to selectively impart movement to rod 111 which is pivotally connected to an arm 112 of the bell crank lever 39, supra, whereby the forward end of the carrier may be elevated or lowered, it being resiliently suspended by virtue of the spring 38 described hereinabove. This arrangement enables crops to be engaged at any selective point depending upon the character of the crops or articles as well as the size thereof. A seat 113 is supported, in this instance, by a more or less flexible member 114 to the frame 10 so that the operator or attendant may comfortably support himself thereon to enable the various remote controls to be selectively actuated to effectively harvest crops of almost any character and growth.

With the arrangement of parts above described, it will be apparent that a machine has been provided having pulling instrumentalities 30 thereon which are adapted to grasp the exposed appendages of soil embedded crops to gradually elevate them along a predetermined path to effect removal thereof and to sever the appendages therefrom. The mouth of the pulling means, in this instance defined by the co-operating conveyor units, is guided in a line coinciding with the rectilinear path along which crops usually are positioned so that the contacting faces of the flexible bands 30 will yieldingly

grasp the exposed portions 25 of the article and carry them along an arcuate path having a gradual incline to slowly pull the crops from the soil subsequent to the loosening thereof by the plow 91, thereby insuring removal of the embedded portion with the exposed ends thereof. The crops are carried to the topping instrumentalities, in this instance the cutters 69, which sever the exposed foliage 25 from the body of the articles or crops, the latter dropping to the auxiliary severing means which are effective to remove any appendages which may be present thereon subsequent to their passage through the cutters 69. The rollers 70, constituting the auxiliary severing means, are adapted to carry any projections therebetween due to the frictional contact of the rollers therewith; however, the body of the article is too large to be drawn therethrough, which necessitates a rupture of the projection from the body, whereafter the inclination of the rollers 70 will effect the discharge of the articles therefrom to any appropriate container which may be suspended from the frame 10.

Various changes may be made in the embodiment of the invention herein specifically described without departing from or sacrificing any of the advantages of the invention as defined in the appended claims.

I claim:

1. A harvester for underground crops, comprising a wheeled frame, arcuately arranged complemental belts on said frame and adapted to withdraw and elevate the plants of said crops, and means on said frame for severing the tops of said plants.

2. A harvester for underground crops, comprising a wheeled frame, arcuately arranged complemental belts on said frame and adapted to withdraw and elevate the plants of said crops, and means for loosening the soil as the plants are emerging therefrom.

3. A harvester for underground crops, comprising a wheeled frame, arcuately arranged complemental belts on said frame and adapted to withdraw and elevate the plants of said crops, means for loosening the soil as the plants are emerging therefrom, and means on said frame for severing the tops of said plants.

4. A harvester for underground crops comprising a wheeled frame, complemental belts on said frame arranged to gradually withdraw and elevate the plants of said crops, and means carried on said frame for loosening the soil as the plants are emerging therefrom.

5. A harvester for underground crops, comprising a wheeled frame, complemental belts on said frame arranged to gradually withdraw and elevate the plants of said crops, means carried on said frame for loosening the soil as the plants are emerging therefrom,

and other means on said frame for severing the tops of said plants.

6. A harvester for underground crops, comprising a wheeled frame, complementary belts on said frame, and adapted to withdraw and elevate the plants of said crops, means on said frame in the path of said belts to sever the plants from the crops, and other means on said frame adapted to receive and remove remaining appendages and projections from said crops.

7. A harvester for underground crops, comprising a wheeled frame, complementary belts on said frame and adapted to withdraw and elevate the plants of said crops, said belts having sections substantially parallel to the ground and other sections angular thereto, and means on said frame for loosening the soil about said plants after said complementary belts have engaged said plants, but anterior to any withdrawing and elevating action thereby.

8. A harvester for underground crops, comprising a wheeled frame, complementary belts arranged on said frame to withdraw and elevate the plants of said crops, cutting means on said frame in the path of said belts to sever the plants from the crops, and other means adapted to receive said crops when severed from said plants and remove appendages and projections therefrom.

9. A harvester for underground crops, comprising a wheeled frame, complementary belts arranged on said frame to withdraw and elevate the plants of said crops, cutting means on said frame in the path of said belts to sever the plants from the crops, and means giving to the crops a path of movement normal to the path of movement of said belts and for severing from said crops other appendages and projections.

10. A harvester for underground crops, comprising a wheeled frame, complementary belts arranged on said frame to withdraw and elevate the plants of said crops, cutting means on said frame in the path of said belts to sever the plants from the crops, and means on said frame for discharging the crops at one side thereof.

50 11. A harvester for underground crops, comprising a wheeled frame, complementary belts arranged on said frame to withdraw and elevate the plants of said crops, cutting means on said frame in the path of said belts to sever the plants from the crops, and means on said frame for conjointly severing other appendages and projections from said crops and discharging the cleaned crop at one side of said frame.

60 12. A harvester for underground crops, comprising a wheeled frame, arcuately arranged complementary belts on said frame to withdraw and elevate the plants of said crops, and circular knives on said frame beneath each of said belts and having cutting

edges projecting beyond the face of the adjacent belt for severing the tops of the plants while being elevated by said belts.

13. A harvester for underground crops, comprising a wheeled frame, arcuately arranged yieldable means disposed in the path of soil embedded plants to yieldably grip the tops thereof to gradually elevate said plants to effect the removal thereof from the soil, rotary cutters in the path of said plants to clip the tops therefrom, and means disposed below said cutters to remove other appendages and projections from the underground parts prior to their discharge from said harvester.

14. A harvester for underground plants, comprising a wheeled frame, complementary arcuately moving belts adapted to gradually remove soil embedded crops having exposed tops, and rotating knives having a plane of revolution sharply angular to the ground for severing the tops from the crop subsequent to the removal of the latter from the soil.

15. A harvester for underground crops, comprising a wheeled frame, an arcuately arranged conveyor carried by said frame to effect the variable elevation of soil embedded crops, cooperating rotary cutters associated with said conveyor to remove the top portions of said crops, and cooperating rolls disposed below said cutters to receive the soil embedded parts and remove additional appendages therefrom, said rolls being inclined to effect discharge of said parts from said frame.

16. A harvester for crops and having a frame, paired arcuate members on said frame and providing opposed complementary tracks, and plant gripping means comprising a pair of cooperating compressible endless conveyors in said tracks.

17. A harvester for crops, comprising the combination of a wheeled frame, paired longitudinally extending arcuate members joined together for unitary adjustment and suspended from said frame, cooperating compressible endless belts adapted to contact with each other and extending about the periphery of said arcuate members, and means responsive to the movement of said frame to drive said belts in unison.

18. A harvester for crops, comprising a wheeled frame, paired cooperating arcuately shaped conveyor supports carried thereby, and endless elastically faced continuous belts on said supports for normally maintaining portions of said conveyors in contact with each other to constitute crop engaging means.

19. A harvester for crops, comprising a wheeled frame, cooperating endless elastically faced conveyors carried thereby, resilient means arcuately disposed for normally maintaining portions of said conveyors in impinging contact with each other to constitute plant engaging means, and means for

pivots supporting said conveyors relative to each other.

20. A harvester for crops, comprising a wheeled frame, a pair of arcuate members on said frame, rotary members journaled in said arcuate members near the extremities thereof, guide members intermediate said rotary members and on said arcuate members, endless chains operatively connected to said rotary members, and endless flexible bands carried by said chains to constitute the contacting surfaces of said chains.

21. A harvester machine for crops, comprising a wheeled frame, arcuately arranged complementary belts for withdrawing and elevating a crop along a predetermined path, said belts having a substantial section arranged substantially parallel to the ground, and soil loosening means for loosening the soil about plants after said plants have been engaged by the sections of said belts parallel to the ground.

22. A harvester for crops, comprising a wheeled frame, arcuately arranged complementary belts for withdrawing and elevating a soil embedded crop along a predetermined path, substantial sections of said belts being disposed parallel to the ground, and soil loosening means for breaking the soil about the crop while said crop is engaged between the section of said belts parallel to the ground and adjustably associated with said frame, and means for adjusting said soil loosening means toward and away from said belts.

23. A harvester for crops, comprising a wheeled frame, a pair of endless conveyors carried thereby, said conveyors being pivotally suspended to present crop engaging surfaces, resilient means to normally maintain said conveyors in operative relation, and a remote control for selectively varying the position of said conveyors.

24. A harvester for crops, comprising a wheeled frame, a pair of arcuately arranged conveyors carried thereby, said conveyors being pivotally suspended to present crop engaging surfaces, resilient means to normally maintain said conveyors in operative relation, and a remote control for selectively varying the position of said conveyors.

25. A harvester for crops, comprising a pair of endless chains disposed in a common plane, driving means in mesh with said chains, a resilient band on each of said chains constituting crop engaging surfaces, and means for yieldingly maintaining said engaging surfaces in contact.

26. A harvester for crops, comprising paired frames in a common plane, endless chains about said frames, driving means in mesh with said chains, a resilient band on each of said chains constituting crop engaging surfaces, and means on said frames for yieldably maintaining said engaging surfaces in contact.

27. A harvester for crops comprising a pair of arcuate supports disposed in a common plane, endless chains about the periphery of said supports, driving means in mesh with said chains, a resilient band on each of said chains to constitute crop engaging surfaces, and means in said supports for yieldably maintaining said engaging surfaces in contact.
